UNITED STATES PATENT OFFICE.

FRANK CONRAD, OF EDGEWOOD PARK, AND ARTHUR B. REYNERS, OF WILKINSBURG, PENNSYLVANIA, ASSIGNS TO WESTINGHOUSE ELECTRIC & MANUFACTURING COMPANY, A CORPORATION OF PENNSYLVANIA.

SWITCH FOR ELECTRIC CIRCUITS.

No. 803,212.

Specification of Letters Patent.

Patented Oct. 31, 1905.

Application filed November 21, 1903, Serial No. 182,196.

To all whom it may concern:

Be it known that we, FRANK CONRAD, residing at Edgewood Park, and ARTHUR B. REYNERS, residing at Wilkinsburg, in the county of Allegheny, State of Pennsylvania, citizens of the United States, have invented a new and useful Improvement in Switches for Electric Circuits, of which the following is a specification.

10 Our invention relates to manually-operated switches for electric circuits.

The object of our invention is to provide a switch of the character indicated which shall be adapted for use in circuits carrying heavy 15 currents; and it consists in means whereby adjustment of the contact-terminals may be made after the switch is closed in order to increase the intimacy of contact between the movable and stationary contact members 20 and whereby the parts may be loosened when it is desired to open the switch.

In the accompanying drawings, Figure 1 is a front elevation of a switch embodying our invention. Fig. 2 is a side elevation of the 25 same. Fig. 3 is a detail sectional view, and Fig. 4 a view, partially in side elevation and partially in section, of a portion of the movable member of the switch shown in the preceding figures.

30 As here indicated the invention is shown as embodied in a single-pole switch of the quick-break type; but it may also be embodied in a multiple-pole switch either with or without a quick-break attachment.

35 One of the terminal blocks 1 is provided with two forwardly-projecting plates 2 and with two rearwardly-projecting screw-threaded studs 3 for attachment to a circuit-terminal at the rear of the switchboard. The 40 other terminal block 4 is also provided with two forwardly-projecting plates 5 and with two rearwardly-projecting screw-threaded studs 6, to which another circuit-terminal is attached.

45 The contact portions of the movable member of the switch consist of two outer blades 7 and 8 and two shorter inner blades 9 and 10. Riveted to the inner faces of the hinged ends of the blades 9 and 10 are wedge-shaped 50 blocks 11 and 12, the thicker edges of the blocks being at their outer ends, and riveted to the inner faces of the other ends of the blades 9 and 10 are similar wedge-shaped

blocks 13 and 14, these blocks being so disposed that the inner faces incline oppositely 55 to those of the blocks 11 and 12.

The blades 7, 8, 9, and 10 and the blocks 11 and 12 are hinged upon a bolt 15, having bearings in the plates 2, which project from the terminal block 1. The ends of the blades 7 6c and 8 are seated in suitable recesses in a head 16 and are fastened therein by means of bolts 17, which extend through the head 16 and the ends of the said blades.

A handle 18, which is provided for opening 65 and closing the switch, has a cylindrical portion 19, that projects through a corresponding opening in the head 16 and makes a sufficiently loose fit therein, so that it may be turned readily upon its axis. The cylindrical portion 19 is provided with a screw-threaded recess or socket, in which is screwed a rod 20, the handle being securely fastened to said rod by means of pins 21. The other 70 end of the rod 20 is provided with an annular 75 groove 22 and projects into a cylindrical recess in a wedge 23, the form and size of which is such that it will accurately fit within the space between the inclined inner faces of the blocks 11 and 12. The wedge 23 is provided 80 with a set-screw 24, the inner end of which is seated in the groove 22 in the rod 20, so that the rod may be readily rotated; but if moved longitudinally the wedge will be moved 85 with it.

A wedge 25 similar to the wedge 23 is located between the blocks 13 and 14 and is provided at its inner thicker end with a screw-threaded bush 26, that is fastened in position by means of a set-screw 27. The bore of the 90 bush 26 is of such diameter that its internal screw-thread makes operative engagement with the screw-thread on the rod 20. The wedge 25 is provided with a lateral opening 28 at approximately its middle part, and a 95 sufficient portion of the thinner edge is cut away to permit of the location and operation therein of the rod 20 without engagement with the adjacent edges.

A bolt 29 projects through the blades 7, 8, 100 9, and 10, and between the inner faces of the blades 9 and 10 it is enlarged to form a cylindrical block 30, which is of less diameter than the opening 28 in the wedge 25 and is provided with a lateral bore 31 to receive the 105 rod 20.

The plates 5 are provided with slots 32, which are either inclined at a suitable angle or are cut upon the arc of a circle having the axis of the bolt 15 as its center in order to receive the ends of the bolt 29 when the movable member of the switch is moved to and from its closed position.

As here indicated the movable member of the switch is provided with a quick-break attachment comprising supplemental blades 33, which are pivoted at one end to the blades 7 and 9 and 8 and 10 by means of pins or bolts 34 and are normally held in engagement with the inner edges of the main blades by means of coil-springs 35, the outer ends of which are supported by means of pins or bolts 36 and the inner ends of which are attached to the blades by similar pins or bolts 37, the frictional engagement between the free ends of the blades and the plates 5 being such that when the switch is opened the supplemental blades will be held in their closed position until the beveled edges 38 at their pivoted ends engage the inner edges of the corresponding main switch-blades. The parts will be so designed that at the time when this engagement is effected the main blades will have become separated from the plates 5, and consequently any arcing which takes place will be between the supplemental blades and the main contact-plates, and on account of the action of the springs 35 the final opening of the circuit will be effected so quickly as to promptly extinguish any arc which may be formed, this being a usual device and well known in the art.

As regards the operation of the main switch, it will be understood that in order to open the switch the handle 18 will be turned in such direction, depending upon whether the screw-thread upon the rod 20 is of the right-hand or left-hand variety, as to tend to move the wedges 23 and 25 toward each other, and therefore out of engagement with the corresponding blocks 11 and 12 and 13 and 14. Since the pressure is exerted in opposite directions, the wedge will first move which has the least frictional engagement with the corresponding blocks, and this movement will continue until the bolt 15 or the cylindrical block 30, as the case may be, comes into engagement with the side of the opening in which it is located. This movement will be sufficient, however, to free the wedge from the adjacent wedge-shaped blocks.

When the movement of either wedge is stopped by the means referred to, the other wedge must necessarily begin to move, and its movement will continue until its bolt 15 or cylindrical block 30, as the case may be, comes into engagement with the adjacent wall of the opening in the wedge, and thus prevents further movement. The switch may then be opened by pulling outward

upon the handle 18, since the blades 7, 8, 9, and 10 are pivotally mounted upon the bolt 15 and the slots 32 in the plates 5 afford passage-ways for the ends of the bolt 29. The friction between the supplemental blades 33 and the plates 5 will serve to maintain the engagement between the said parts until the beveled edges 38 engage the adjacent edges of the main blades, and thereafter the main and supplemental blades will move together until the latter are nearly freed from contact with the plates 5, when the springs 35 will effect a quick separation of said parts and will move the supplemental blades into their normal edge-to-edge engagement with the main blades. When the switch is again closed, by moving the handle inward until the blades occupy the positions indicated in Fig. 2 the handle may be rotated in the opposite direction to that above described, so as to move the wedges away from each other into engagement with the faces of the corresponding wedge-shaped blocks. This action, as will be readily understood, serves, in conjunction with the bolts 15 and 29, to draw the blades 7 and 9 and 8 and 10 into close contact with the corresponding plates 2 and 5, and thus insures a maximum carrying capacity for the amount of metal embodied in the switch.

The form and dimensions of the several parts may obviously be varied from what is shown, and we therefore do not intend to limit our invention to details of construction, except as limitations may be imposed by the state of the art.

We claim as our invention—

1. In a switch for electric circuits, the combination with two pairs of stationary contact-terminals, of a movable member comprising contact-blades having inclined surfaces, bolts, oppositely-acting wedges and means for actuating said wedges to engage said inclined surfaces and clamp said blades to both pairs of stationary terminals.

2. In a switch for electric circuits, the combination with two pairs of stationary contact-terminals, of a movable member comprising contact-blades having lateral projections, clamping-wedges and means for moving said wedges in opposite directions to engage said projections.

3. In a switch for electric circuits, the combination with two pairs of stationary contact-terminals, of a movable member pivoted to one of said pairs of terminals and comprising contact-blades having inclined surfaces, clamping-wedges and means for moving said wedges in opposite directions against said inclined surfaces.

4. In a switch for electric circuits, the combination with two pairs of stationary contact-terminals, of a movable member comprising contact-blades having oppositely-inclined surfaces which are in lateral alinement with the stationary terminals when the switch is

closed, wedges located between said inclined surfaces and means for moving said wedges in opposite directions to clamp and release the contact-blades.

5 5. In a switch for electric circuits, the combination with two pairs of stationary contact-terminals, of a movable member comprising inner and outer blades the former of which have wedge-shaped blocks, wedges located between said blocks and means for forcing said wedges in opposite directions into and out of engagement with said blocks.

10 6. In a switch for electric circuits, the combination with two stationary terminals, of a movable member comprising contact-blades having inclined surfaces, wedges for engaging said inclined surfaces to clamp said blades to the contact portions of said stationary terminals and a single means for actuating said wedges in opposite directions.

15 7. In a switch for electric circuits, the combination with two stationary terminals, of a movable member comprising contact-blades, connecting-bolts and wedge-shaped blocks, wedges located between said blocks and means for moving said wedges in opposite directions to clamp the contact portions of both stationary terminals between the blades of the movable member.

20 8. In a switch for electric circuits, the combination with two pairs of stationary contact-terminals, of a movable member hinged or pivoted to one of said pairs of terminals and comprising contact-blades having oppositely-inclined surfaces which are in lateral alignment with the stationary terminals when the switch is closed, wedges located between said inclined surfaces and means for moving said wedges in opposite directions to clamp and release the contact-blades.

25 9. In a switch for electric circuits, the combination with two pairs of stationary contact-terminals, of a movable member hinged or pivoted to one of said pairs of terminals and comprising inner and outer blades the former of which have wedge-shaped blocks, wedges located between said blocks and means for forcing said wedges in opposite directions into and out of engagement with said blocks.

30 10. In a switch for electric circuits, the combination with two stationary terminals, of a movable member pivoted or hinged to one of said terminals and comprising contact-blades having lateral projections, wedges for engaging said projections to clamp said blades to the contact portions of said stationary terminals and a single means for actuating said wedges in opposite directions.

35 11. In a switch for electric circuits, the combination with two stationary terminals, of a movable member hinged or pivoted to one of said terminals and comprising contact-blades, connecting-bolts and wedge-shaped blocks, wedges located between said blocks and means for moving said wedges in

opposite directions to clamp the contact portions of both stationary terminals between the blades of the movable member.

40 12. In a switch for electric circuits, two pairs of stationary contact-terminals, a quadruple-blade member having wedge-shaped blocks attached to the inner faces of the inner blades, two wedges and means for forcing them in opposite directions between said blocks. 75

13. In a switch for electric circuits, the combination with two pairs of stationary contact-terminals, of a quadruple-blade member having two pairs of wedge-shaped blocks attached to the inner faces of the inner blades, a rotatable handle having a screw-threaded rod and oppositely-disposed wedges mounted upon said rod and adapted to be forced in opposite directions between the respective pairs of blocks when the handle is rotated in the proper direction. 80

14. In a switch for electric circuits, the combination with two pairs of side-by-side, stationary contact-terminals, of a movable contact-terminal comprising two pairs of blades having inclined surfaces, two oppositely-acting wedges to engage said surfaces, an operating screw-rod therefor and an actuating-handle for said rod. 85

15. In a switch for electric circuits, the combination with stationary contact-terminal plates and contact-terminal blades having lateral projections and engaging both faces of said plates, of bolts, wedges for engaging the projections on said blades and means for adjusting the wedges to increase or decrease the clamping action. 90

16. In a switch for electric circuits, two pairs of stationary contact-terminals, a quadruple-blade member pivoted to one of said pairs of terminals and having wedge-shaped blocks attached to the inner faces of the inner blades, two wedges and means for forcing them in opposite directions between said blocks. 105

17. In a switch for electric circuits, the combination with two pairs of stationary contact-terminals, of a quadruple-blade member pivoted to one of said pairs of terminals and having two pairs of wedge-shaped blocks attached to the inner faces of the inner blades, a rotatable handle having a screw-threaded rod and oppositely-disposed wedges mounted upon said rod and adapted to be forced in opposite directions between the respective pairs of blocks when the handle is rotated in the proper direction. 110

18. In a switch for electric circuits, the combination with two pairs of side-by-side, stationary contact-terminals, of a movable contact-terminal hinged or pivoted to one of the pairs of stationary terminals and comprising two pairs of blades having oppositely-inclined faces, two oppositely-acting wedges to engage said faces, an operating screw-rod 125

therefor and an actuating-handle for said rod.

19. In a switch for electric circuits, the combination with a pair of stationary contact-
5 terminals, of a movable member having op-
positely-acting wedges and a blade so formed
and arranged as to be clamped laterally
against the stationary contact-terminals by
said wedges.
- 10 20. In a switch for electric circuits, the
combination with two pairs of stationary con-
tact-terminals, of a movable member having

a pair of oppositely-acting wedges and con-
tact-blades so formed and arranged as to be
clamped to the stationary contact-terminals 15
by the said wedges.

In testimony whereof we have hereunto
subscribed our names this 6th day of Novem-
ber, 1903.
